UNITED STATES PATENT OFFICE.

HENRY DOUCHAMP, OF MOUNT JEWETT, PENNSYLVANIA, ASSIGNOR TO SMETHPORT GLASS COMPANY, OF SMETHPORT, PENNSYLVANIA, A CORPORATION OF WEST VIRGINIA.

GLASS-FURNACE.

979,935.

Specification of Letters Patent. Patented Dec. 27, 1910.

Application filed November 18, 1908. Serial No. 463,264.

To all whom it may concern:

Be it known that I, HENRY DOUCHAMP, a citizen of the United States, residing at Mount Jewett, in the county of McKean and State of Pennsylvania, have invented new and useful Improvements in Glass-Furnaces, of which the following is a specification.

The invention relates to an improvement in glass furnaces, and is particularly directed to a construction for facilitating the proper withdrawal of the material from the furnace.

In manufacturing window glass by machinery it has been practically impossible from the commercial standpoint to draw the glass from the furnace without spoiling a large amount of material, owing to the necessity for cooling and reheating incident to the use of such apparatus as has been known in the art.

The present invention is particularly designed to obviate the above noted disadvantage and to so arrange for the drawing of the furnace as to insure a natural cooling of the glass in drawing and a natural reheating of the material after severance of the cylinder, thereby insuring a uniform result and perfecting to a commercial success the manufacture of window glass by machinery.

The invention will be described in the following specification, reference being had particularly to the accompanying drawings, in which:—

Figure 1 is a view in section, partly in elevation, illustrating the improvement. Fig. 2 is a plan of the furnace.

Referring particularly to the accompanying drawings, I have illustrated a conventional form of furnace 1 including side and end walls 2 and 3, which showing is intended to indicate any desired form or structure of furnace in which the glass, as 4, may be maintained in a molten state.

The top of the furnace is formed to provide two alined draw openings 5 and 6, said furnace top being otherwise closed against the escape of heat. As a preferred form of closure for the top of the furnace I provide what may be termed cap plates 7 and 8 arranged respectively in contact with the side walls 2 and end walls 3, as shown in Fig. 2. The cap plates are respectively of materially less width than half the width of the furnace, thereby providing a space centrally of

the furnace between the proximate edges of the cap plates. The space thus formed is sealed against the escape of heat by tiles 9, which may be supported in any desired way as by bolts 10 pendent from an overlying beam 11 or the like. The respective tiles are so arranged and formed as to provide the draw openings 5 and 6, as clearly shown in Fig. 2, and are of materially greater height than the thickness of the cap plates 7 and 8. As the upper surfaces of the cap plates are alined with the upper surface of the furnace walls and as the tiles are of a height to terminate at their lower edges just above the highest level of the molten glass within the furnace, it will be understood that between each side wall 2 and the adjacent tile 9 there is provided a chamber 12, bound at the top by the cap plate, at the ends by the furnace walls 3, and at the sides by the side wall 2 and the outermost tile 9. These chambers, which will be hereinafter termed the heating chambers, are open at the bottom for direct communication with the body of the furnace carrying the molten glass, and consequently the temperature in the chambers will be practically that of the molten material.

As an essential part of the present invention I have constructed what I term a glass carrier, including a body 13 and a series of rings, as 14, 15, 16, and 17, which rings are of duplicate construction and having an interior diameter which may be equal to or present any desired variation from the diameter of the draw openings 5 and 6. The body 13 is formed with diametrically opposed rounded depressions 18, corresponding to the curvature of the rings and designed to receive the rings, complementary dovetailed connections being formed on the body and rings whereby the latter may be removably secured to the former. The body and rings are of approximately equal thickness, and are constructed of any desired refractory material, the arrangement of parts providing for the disposition of the rings in diametrically opposed pairs and so spaced that when the body is in proper position each of the rings of a particular pair will exactly register with the draw openings 5 and 6 of the furnace. With the operative pair of rings registering with the draw openings the remaining pair thereof will be disposed in alinement at right angles to a line joining the draw openings, and, therefore, within

the plane of the heating chambers 12. The body 13 is centrally provided with a vertically projecting stud 20 of angular contour, forming a head adapted to receive a socket member 21 fixed on the lower end of a rod 22 which extends through a well 23 in the tile construction and above the furnace is provided with a bevel gear 24 adapted to be engaged and operated by a bevel pinion 25 carried on a power shaft 26.

An essential and important characteristic of the present invention resides in the manner of supporting the glass carrier. As will appear as the description proceeds it is essential that the molten glass should be used as a medium for reheating the glass cut off after drawing the cylinder, and, therefore, the rings must at all times be subjected to the direct action of the molten glass. For this purpose the glass carrier including the body and rings is supported directly in the molten material, or in other words the glass carrier floats in the molten glass. The specific gravities of the molten glass and material composing the carrier are such that the latter will float in the former with its upper surface practically level with the level of the glass. Another advantage of this arrangement is that the rings are thereby at all times filled with the molten material and furthermore the carrier as a whole will always maintain the same relative position in the body of the molten material independent of the height or level of the same. It is, of course, understood that the connection between the stud 20 and the socket 21 is such as to permit the carrier proper to remain at all times in the body of the glass independent of the height or level of the same, and that the stud will be of such height as to permit coöperation of the socket in any position of the carrier.

In operation the power shaft is actuated to arrange two of the rings, as 14 and 15, in alinement with the draw openings 5 and 6. The drawing apparatus, which may be of any desired type, is then operated to draw through the rings and openings the desired quantity of material, which as understood in this art will be in the form of a cylinder of the desired length. After severing the drawn portion from the ring, it will be obvious that a quantity of material will remain within and somewhat beyond the ring which has been subjected to a cooling action, and, therefore, the ring is not clear. Immediately succeeding the drawing operation the power shaft is again actuated to aline the remaining pairs of rings 16 and 17 with the draw openings. This movement will, of course, operate the rings 14 and 15 from which the previous drawing has been made, to dispose them beneath the cap plates 7 and 8, or in the heating chambers 12. In this position the more or less set material re-

maining in these rings after drawing is subjected to a natural reheating, with the effect to efficiently clear said rings for the next drawing operation.

It will be apparent from the above described construction that the carrier may be continuously rotated in one direction or rotatively reciprocated through a quarter revolution or through a half revolution, the object desired being to arrange the proper rings in alinement with the draw openings and dispose the remainder in the heat chambers.

The salient feature of the present invention is the use of a ring through which the molten material is to be drawn, which ring is at all times floating in the molten material. Obviously the device may include any desired number of rings, four being shown as a matter of convenience.

Having thus described the invention what is claimed as new, is:—

1. A reservoir adapted to contain molten glass and formed with a draw opening, a plurality of elements floating in the material and through each of which the material may be drawn, and means for operating the elements to cause their successive registry with the draw openings.

2. A reservoir adapted to contain molten glass, a carrier supported solely by the molten material, said carrier including a plurality of elements through which the material may be drawn, and means for operating the carrier.

3. A reservoir adapted to contain molten glass and formed with a draw opening, a carrier arranged in the reservoir and supported solely by the molten material, said carrier including a plurality of elements through which the material may be drawn, and means for operating the carrier to cause the successive registry of the elements with the draw opening.

4. A reservoir adapted to contain molten glass and formed with a draw opening, said reservoir including a chamber open to the heat from the molten material, a carrier arranged in the reservoir and supported solely by the molten material, said carrier including a plurality of elements through which the material may be drawn, and means for operating the carrier to cause the successive registry of the elements with the draw opening and with the chamber.

5. A reservoir adapted to contain molten glass and formed with a plurality of draw openings, said reservoir including a plurality of heat chambers beyond the opening, a carrier arranged in the reservoir and supported solely by the molten material, said carrier including a plurality of elements arranged in diametrically opposed pairs, and means for operating the carrier to register the elements of a particular pair with the

draw openings, the respective elements being so disposed as to arrange one pair thereof within the heat chambers when another pair is in registry with the draw openings.

5. 6. A reservoir adapted to contain molten metal and formed with a draw opening, a carrier supported by the molten material and including a plurality of elements adapted for coöperation with the draw opening, 10 and means for operating the carrier to dispose any of said elements in registry with the draw opening.

7. A reservoir adapted to contain molten glass and formed with a draw opening, a carrier arranged in the reservoir and supported solely by the molten material, a ring connected to the carrier and at all times in the material, and means for operating the carrier to position said ring into or out of 20 registry with the draw opening.

8. A furnace formed with a draw opening adapted to contain molten metal, a carrier arranged in the furnace and supported solely by the molten metal therein, a ring remov- 25 ably connected to the carrier, and means for operating the carrier to position the ring into or out of registry with the opening.

9. A furnace adapted to contain molten metal and formed with a plurality of draw 30 openings, a carrier floating in the furnace, means for operating the carrier, and a series of draw elements connected to the carrier and operable therewith, said elements exceeding in number the number of draw open- 35 ings.

10. A furnace adapted to contain molten metal and formed with a plurality of draw

openings, a carrier floating in the furnace, means for operating the carrier, and a series of draw elements connected to the carrier and 40 operable therewith being so arranged as to insure the simultaneous registry of a plurality thereof with the draw openings.

11. A furnace adapted to contain molten metal and formed with a plurality of draw 45 openings, a carrier floating in the furnace, means for operating the carrier, and a series of draw elements connected to the carrier and operable therewith being so arranged as to insure the simultaneous registry of a 50 plurality thereof with the draw openings and the disposition of the remaining elements within the furnace wholly beyond the draw openings.

12. A glass furnace having a stirrer sup- 55 ported solely by the molten glass, and means for actuating said stirrer, the connection between the stirrer and its actuating means being such as to permit the stirrer to rise and fall with the changing level of the molten 60 glass.

13. A glass furnace having a rotatable stirrer supported solely by the molten glass, and means for rotating said stirrer, the connection between the stirrer and its rotating 65 means being such as to permit the stirrer to rise and fall with the changing level of the molten glass.

In testimony whereof I affix my signature in presence of two witnesses.

HENRY DOUCHAMP.
